Primary Examiner — Lilyana Bekic(74) *Attorney, Agent, or Firm* — Dann, Dorfman, Herrell and Skillman; Stephen Eland(57) **CLAIM**

The ornamental design for an intra-articular injection device, as shown and described.

DESCRIPTION

FIG. 1 is a front, top, left perspective view of an intra-articular injection device showing our design therefor;

FIG. 2 is a bottom, rear, right perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

Throughout the drawings, broken lines depict portions of the intra-articular injection device that form no part of the design.

1 Claim, 8 Drawing Sheets---
